UNITED STATES PATENT OFFICE

FRANK B. BREMERMAN, OF INDIANAPOLIS, INDIANA

DESIGN FOR A MUSICAL INSTRUMENT BODY

Application filed June 19, 1930. Serial No. 36,101. Term of patent 3½ years.

To all whom it may concern:

Be it known that I, FRANK B. BREMERMAN, a citizen of the United States, residing at Indianapolis, in the county of Marion, and State of Indiana, have invented a new, original, and ornamental Design for a Musical Instrument Body, of which the following is a specification, reference being had to the accompanying drawings, forming part thereof.

In the drawings,—Figure 1 represents a front view of a musical instrument body, showing my new design; Fig. 2 is a side view thereof.

I claim:

The ornamental design for a musical instrumental body, as shown.

In testimony whereof, I affix my signature on the 12th day of June, 1930.

FRANK B. BREMERMAN.
